C. W. HARVEY

CLIPPING MACHINE

Filed June 24, 1921

Inventor

C. W. Harvey

By *D. Swift*

Attorney

UNITED STATES PATENT OFFICE.

CHARLES W. HARVEY, OF EAST LYME, CONNECTICUT.

CLIPPING MACHINE.

Application filed June 24, 1921. Serial No. 480,024.

To all whom it may concern:

Be it known that I, CHARLES W. HARVEY, a citizen of the United States, residing at East Lyme, in the county of New London, 5 State of Connecticut, have invented a new and useful Clipping Machine; and I do hereby declare the following to be a full, clear, and exact description of the invention, such as will enable others skilled in the art to 10 which it appertains to make and use the same.

The invention relates to clipping machines and has for its object to provide a clipping machine particularly of the type used for 15 clipping hair and so constructed that the same will be operated through the medium of a spring motor, thereby obviating the manual operation of hair clippers as at present constructed.

20 A further object is to provide a hair clipping machine comprising a casing having rotatably mounted therein a spring actuated operating shaft, a toothed wheel carried by said shaft, with which wheel a spring 25 actuated detent cooperates. Also to provide fan means and spring actuated means for retarding the rotation of the shaft and the cutting element during a hair clipping operation.

30 With the above and other objects in view the invention resides in the combination and arrangement of parts as hereinafter set forth, shown in the drawings, described and claimed, it being understood that changes 35 in the precise embodiment of the invention may be made within the scope of what is claimed without departing from the spirit of the invention.

In the drawings:

40 Figure 1 is a top plan view of the clipping machine.

Figure 2 is a longitudinal sectional view through the clipping machine, taken on line 2-2 of Figure 1.

45 Figure 3 is a vertical transverse sectional view taken on line 3-3 of Figure 2.

Figure 4 is a transverse sectional view taken on line 4-4 of Figure 2.

Referring to the drawings, the numeral 50 1 designates a cylindrical handle member and 2 the removable cap carried thereby. The forward end of the handle member 1 is provided with a tapered portion 3 and extending through the chamber 4 of said tapered portion and the chamber 5 of the handle member 1 is a shaft 6. Shaft 6 at

one of its ends is rotatably mounted in a bearing 7, and its other end is rotatably mounted in a bearing 8 of the removable cap 2. Surrounding the shaft 6 is a spiral spring 9, one end of which is anchored at 10 in the removable cap 2 and the other end anchored at 11 in a ratchet wheel 12. Pivoted at 13 to a casing 1 and extending through an aperture 14 therein is a spring 60 actuated dog 15, which dog holds the ratchet wheel 12 against retrograde movement when the coiled spring 9 is tensioned by rotating the shaft 6 through the medium of the finger 65 engaging member 16 detachably carried by the rear end of the shaft 6. It will be seen that when the shaft 6 and the ratchet wheels 12 are rotated in the direction of the arrow *a* that the nose of the spring actuated pawl 15 will slide over the ratchet teeth of the 70 ratchet wheel and hold said ratchet against retrograde movement when the finger engaging member 16 is released, thereby maintaining the coiled spring 9 tensioned. 75

The forward end of the casing 1 terminates in spaced flanges 17 and 18, which flanges are in parallel relation to each other, and secured to the flange 18 is a plate 19 having stationary fingers 20, which fingers form cutter bars for shearing hair as the 80 knife fingers 21 carried by the knife blades 22 are moved transversely over the plate 19. Knife blade 22 is provided with a vertically disposed slot 23 in which is mounted a slide- 85 able bearing block 24, and with which slide- 90 able bearing block the crank 25 of the shaft 6 engages. It will be seen that as the shaft 6 rotates the knife blade 22 will be recipro- 95 cated thereby causing its cutter fingers 21 to reciprocate across the fingers 20 of the plate 19, and against which fingers the hairs are sheared.

In operation the operator when he desires to reciprocate knife blade 22 presses downwardly on the spring actuated pawl 15. 100

Knife blade 22 is provided with an upwardly extending flange 26, which is guided in a transversely disposed slot 27 in the flange 17. However, it has been found that to prevent a too rapid reciprocation of the 105 knife blade 22 that retarding means must be provided for the shaft 6 and the blade 22. To accomplish this result the shaft 6 is provided with fan blades 28, which when rapidly rotated act upon the air and retard the rotation of the shaft to a certain extent. However to additionally retard said rotation 110

a leaf spring 29 is disposed in a transversely disposed slot of the knife blade 22 and is bowed upwardly. Spring 29 is upwardly bowed and the frictional engagement of the 5 ends thereof with the bottom of the groove 30 are regulated by the adjusting screw 31 in such a manner that the reciprocation of the knife blade 22 may be increased or reduced in speed as desired.

10 From the above it will be seen that a hair clipping machine is provided which is simple in construction and one wherein the cutting blade is reciprocated through the medium of a coiled tensioned spring. Also 15 that said coiled tensioned spring may be controlled as desired for reciprocating the cutting knife.

The invention having been set forth what is claimed as new and useful is:—

20 A clipping machine comprising a casing, a finger bar secured to the forward end of the casing, a flange carried by the casing and overlying said finger bar and provided

with a transversely disposed slot, a knife blade disposed on the finger bar and having 25 a tongue and groove connection therewith, a transversely disposed rib carried by the knife blade and disposed in the transversely disposed slot of the overlying flange, a drive shaft, a crank pin connection between the 30 shaft and the rear end of the knife blade, a transversely disposed bowed leaf spring disposed in a transversely disposed slot in the knife blade, and an adjusting screw extending through the overlying flange and forming means whereby the frictional engagement of the bowed leaf spring may be varied.

In testimony whereof I have signed my name to this specification in the presence of 40 two subscribing witnesses.

CHARLES W. HARVEY.
